UNITED STATES PATENT OFFICE

162,839

AUTOMOBILE FENDER

Aloysius J. Kaminski, Detroit, Mich., assignor to
Chrysler Corporation, Highland Park, Mich., a
corporation of Delaware

Application August 13, 1949, Serial No. 4,467

Term of patent 7 years

(Cl. D14—6)

To all whom it may concern:

Be it known that I, Aloysius J. Kaminski, a citizen of the United States, residing in the city of Detroit, county of Wayne, and State of Michigan, have invented a new, original, and ornamental Design for an Automobile Fender, of which the following is a specification, reference being had to the accompanying drawing, forming part thereof, in which:

Fig. 1 is a side elevation of an automobile fender incorporating my novel design;

Fig. 2 is a top plan view thereof;

Fig. 3 is a front elevation of the fender with a flange portion shown in broken lines;

Figs. 4, 5 and 6 are sections taken on the lines 4—4, 5—5 and 6—6 of Fig. 1; and

Fig. 7 is a section taken on the line 7—7 of Fig. 3.

The characteristic features of my design are shown in full lines in the drawing.

I claim:

The ornamental design for an automobile fender, substantially as shown and described.

ALOYSIUS J. KAMINSKI.
